DESIGN FOR A COMBINATION ELECTRIC CIGARETTE LIGHTER AND DISPENSER

Harley H. La Vercombe, Detroit, Mich.

Application July 21, 1933. Serial No. 48,779

Term of patent 7 years

To all whom it may concern:

Be it known that I, HARLEY H. LA VERCOMBE, a citizen of the United States, residing at Detroit, in the county of Wayne and State of Michigan, have invented a new, original, and ornamental Design for Combination Electric Cigarette Lighters and Dispensers, of which the following is a specification, reference being had to the accompanying drawing, forming part thereof.

In the drawing:

I claim:

The ornamental design for a combination electric cigarette lighter and dispenser, as shown.

HARLEY H. LA VERCOMBE.
